UNITED STATES PATENT OFFICE

DANIEL H. MILLER, OF KEARNEY, NEBRASKA

TIRE TUBE TESTER

Application filed September 5, 1928, Serial No. 304,041. Renewed February 3, 1932.

The present invention relates to devices for testing inner tubes of pneumatic tires in order to locate punctures or other air leaks within the inner tubes which are not readily visible to the eye and having for its object 5 to provide a portable device designed to submerge inner tubes within a tank of water wherein the rising air bubbles will indicate the exact location of such leak.

10 It is also among the important objects of the invention to provide a portable apparatus of the character described of a simple, durable and knockdown construction which may be readily and easily dismantled and arranged in a compact manner so that the complete apparatus will take up but a minimum amount of space during shipment thereof.

Still another object of the invention is to provide an inner tube testing device of the 20 character set forth with a tube submerger capable of being retained in an elevated position when not in use and locked in a submerged position whereby the tube will be retained in the water and the operator having 25 his hands free to move the tube within the water so as to make a complete inspection of the same.

With the above and other objects in view the invention may be said to consist of novel 30 features of construction, combination and arrangement of parts that will be hereinafter more fully described and particularly pointed out in the appended drawings in which:

Figure 1 is a front elevation of the apparatus embodying the present invention,

Figure 2 is a top plan view thereof,

Figure 3 is a detail view of the locking device as is taken on the line 3—3 of Figure 1, in the direction of the arrows as shown thereon,

40 Figure 4 is a vertical horizontal section through the entire machine showing the submerger when in its elevated position,

Figure 5 is a similar view to that shown in Figure 4, showing the position of the submerger when retaining the inner tube within the tank of water,

Figure 6 is a top plan view of the table or support, and

Figure 7 is a detailed perspective view of 50 the submerger.

Referring now more particularly to the drawings wherein like and corresponding parts are designated by similar reference characters throughout the several views, the apparatus as herein disclosed comprises a suitable table or support having detachably mounted thereupon a tank containing water in which is adapted to be submerged the inner tube of a pneumatic tire indicated herein by the letter T which is to be tested. Detachably connected to this tank or water holder is a suitable support or bracket carrying a submerging device which is adapted to retain the inner tube in a submerged position within the water contained in the tank.

The table or holder for the apparatus is preferably made of three posts indicated by the numeral 1 and each being made of angle iron as shown. These posts 1 are connected by upper and lower braces indicated by the numerals 2 and 3 respectively, each of which consisting of flat bars bent in the form of a triangle as better illustrated in Figure 6, having their corners riveted or otherwise secured to the posts 1 as is indicated by the numeral 4 and the opposite ends of each band are riveted or otherwise secured together as indicated by the numeral 5. The braces 2 not only rigidly connect the supporting posts 1 but also provide a shelf for supporting a tank 6 in the manner as is to be later set forth.

This tank 6 is also preferably made of sheet metal and of a circular formation having a reinforcing band 7 secured to the upper end thereof. This tank 6 is to contain water up to the level of that shown in Figure 4 whereby an ordinary inner tube may be submerged within this water and the arising bubbles therefrom will correctly indicate any punctures or air leaks within this inner tube.

In order to submerge this inner tube within the water contained within the tank and retain the same in its submerged position, a spider shaped submerger 8 is provided and which is better illustrated in Figure 7 of the drawings. This spider shaped submerger consists of four U-shaped members being connected or riveted together along certain of their sides as indicated by the numeral 9, forming a central bearing block 10 and four 95 100

rigidly projecting arms each terminating in Y-shaped ends 11. This submerger is carried by a vertically movable shaft 12 and is detachably connected thereto by extending the 5 lower end of the shaft through the hub portion 10 of the submerger and locking the submerger to the shaft by means of the locking nut 13. Interposed between the opposite faces of the submerger 8 and the locking nut 10 13 are the plates 14 which plates greatly increase the strength of the radially projecting arms of this submerger.

Detachably connected to the tank 6 and supporting the shaft 12 of the submerger is 15 a bracket consisting of a vertically extended bar 15 having its lower end detachably connected by means of the bolt 16 to the tank 6 and its upper extremity bent at right angles thereto in order to form a bearing support 17 20 through which extends the upper end of the shaft 12. Also detachably connected as at 18 to the diametrically opposed sides of the tank 6 is a U-shaped bar 19 having an opening formed within the medial portion thereof 25 through which extends the shaft 12. The horizontally extending bar 20 connects the bars 15 and 19 and a vertically extending bar or rod 21 connects the bar 20 with the upper end 17 of the bar 15. A bar 22 has its opposite 30 ends connected to the bar 19 and its medial portion connected to the horizontal portion 17 of the bar 15. Pivotally connected to the bar 15 as at 23 is a lever 24. This lever is 35 preferably made of a strip of sheet metal bent upon itself to form a handle 25 at one end thereof and its opposite end extending within the bar 15 and pivotally connected thereto as at 23. The rod 21 extends through this lever 24 so as to form a guide therefor and the shaft 40 12 is provided with a reduced portion 26 in order to form a connection between the shaft 12 and this lever. The opposite sides of this lever are retained within the groove 26 of the shaft 12 by means of the bolt 27 and a 45 spacer is arranged between the opposite sides of the lever so as to prevent a too tight connection between the shaft 12 and this lever whereby the shaft will be free to rotate within the lever but will be caused to move in a 50 vertical direction by the swinging of the lever upon its pivot connection 23. From this construction it is obvious that when the operator grasps the handle 25 and swings the lever upon its pivoted connection the shaft 12 may 55 be raised or lowered and likewise the submerger carried by the shaft 12 will be caused to travel therewith.

In order to retain this submerger in an elevated or submerged position, I provide a 60 locking device which consists of a plate 28 pivotally mounted as at 29 upon the bar 19. This plate is provided with a handle 30 at one end thereof and its opposite end is connected by means of a coil spring 31 to the bar 65 21 and formed within the plate 28 is a recess

32. The shaft 12 has formed therein a pair of spaced grooves indicated by the numerals 33 and 34 respectively which are to receive this plate 28 for limiting the vertical movement of the shaft 12. From this construction 70 it is obvious that when it is desired to elevate and retain in an elevated position the submerger 8, the shaft 12 is raised to the position as shown in Figure 4 whereat the plate 28 will seat itself within the groove 34 of the shaft 12 and as the recess 32 of this plate is of less diameter than that of the shaft 12 it will, when seated within this groove 34, prevent the vertical movement of the shaft 12 and likewise the submerger carried thereby. 75 When it is desired to submerge the tube within the tank the operator will release the latch member 28 by pulling upon the handle 30 thereof against the tension of the spring 31, and pushing down on the handle 25 causes the submerger to enter the tank. By releasing the handle 30 of this locking plate the latter will engage the groove 33 of the shaft 12 thereby holding the submerger and the tube submerged in the position as illustrated 80 in Figure 5 of the drawings. From the foregoing construction it is apparent that an operator may submerge an inner tube within the water contained within the tank and lock this inner tube in a submerged position as is shown in Figure 5 of the drawings thereby permitting his hand to be free so that he may turn or otherwise inspect the tube T within the tank while being submerged therein. Likewise, when the submerger is raised to 90 the position as illustrated in the Figure 4, it will be locked and retained in this position so that another tube may be substituted for the tube previously inspected and removed from the tank.

When the device is presented for use the tank 6 rests upon the shelf 2 as is better illustrated in Figures 1 and 6 of the drawings and the projection end 35 of the post 1 retains this tank in position upon the braces 2 or shelf 100 of the support therefor.

Manifestly, the construction shown is capable of considerable modification and such modification as is within the scope of my claims, I consider within the spirit of my invention.

I claim:

1. A tire tube tester comprising a support composed of structural elements, a tank detachably mounted upon said support, a bracket detachably connected to said tank, a spider-shaped tube submerger supported by said bracket, a lever pivotally connected to said bracket and means for operatively connecting said lever with said tube submerger whereby the latter may be manually raised or lowered.

2. A tire tube tester comprising a stand, a tank removably supported upon said stand, a bracket detachably connected to said tank,

an upright shaft rotatably and slidably mounted within said bracket, a tube submerger secured to the lower end of said shaft, a lever pivotally mounted upon said bracket and connected to said shaft whereby said shaft and tube submerger carried thereby may be raised and lowered and means for locking such shaft in its raised or lowered position.

3. A tire tube tester comprising a tank, a bracket connected to said tank, an upright shaft rotatably and slidably mounted within said bracket, a spider shaped submerger carried by the lower end of said shaft, a lever pivotally mounted upon said bracket and connected to said shaft for raising and lowering said tube submerger, and a spring actuated locking member adapted to engage such shaft for retaining the latter in its raised or lowered position.

4. A tire tube tester comprising a stand, a tank supported upon said stand, a vertically extending bar having one end secured to said tank, an inverted U-shaped bar having its opposite ends secured to said tank, a horizontal bar connecting said vertical and U-shaped bar, a shaft extending through said bars, a tire tube submerger carried by said shaft, a lever pivotally connected to said vertical bar and to said shaft whereby the shaft may be raised and lowered, and a vertical guide rod for said lever and connected to said vertical bar and said horizontally arranged bar.

In witness whereof I have hereunto set my hand.

DANIEL H. MILLER.
